B. SAKREN.

WINDOW GUARD.

APPLICATION FILED DEC. 10, 1912.

1,095,422.

Patented May 5, 1914.

UNITED STATES PATENT OFFICE.

BENJAMIN SAKREN, OF BROOKLYN, NEW YORK.

WINDOW-GUARD.

1,095,422.

Specification of Letters Patent. Patented May 5, 1914.

Application filed December 10, 1912. Serial No. 736,033.

To all whom it may concern:

Be it known that I, BENJAMIN SAKREN, a citizen of the United States, residing at Brooklyn, in the county of Kings and State of New York, have invented new and useful Improvements in Window-Guards, of which the following is a specification.

An object of the invention is to provide a guard for use on windows and the like, to prevent persons from accidentally falling out of the window.

The invention embodies among other features a guard which, when not in use, can be conveniently folded into a box supported on the window casing, the said guard and box being arranged on the window casing so as not to interfere with the operation of the sash or with the placing of screens in the casing.

In the further disclosure of the invention reference is to be had to the accompanying drawings, constituting a part of this specification, in which similar characters of reference denote corresponding parts in all the views, and in which:

Figure 1 is a fragmentary elevation of a window casing showing my device applied thereto; Fig. 2 is a vertical sectional view taken through the box showing my device folded therein; and Fig. 3 is a vertical sectional view taken on the line 3-3 in Fig. 1. Fig. 4 is a vertical sectional view taken on the line 4-4 in Fig. 1.

Referring more particularly to the views, I disclose a guard 10 consisting of a plurality of parallel strips 11, 12 having cross strips 13 pivotally connected thereto, the inner end of the strip 11 having pivotal connection with a window casing 14, as shown, so that when the guard 10 is swung upwardly the cross strips 13 swinging on the strip 11 will bring the strip 12 into position adjacent the strip 11, thus folding the guard.

In order to secure the guard 10 in a horizontal and unfolded position, a spring-like locking member 15 is secured to the window casing at a point opposite to the point of pivotal connection of the guard with the window casing, the said locking member being preferably formed of a single piece of material having one end thereof rigid with the window casing and the other end thereof loosely engaging the window casing in view of the spring-like action of the material from which the locking member 15 is made. Now when the guard 10 is swung down-

wardly into an unfolded position, the strip 12 of the guard will strike the free downwardly inclined end of the locking member with sufficient force to move the said end out of engagement with the casing so that the guard can swing downwardly within the locking member, the spring-like action of the material from which the locking member is made causes the free end of the locking member to remain in engagement with the window casing, thus locking the guard in open position on the window casing. In order to further secure the guard in open position a hook 16 is mounted to swing on the window casing beneath the point of pivotal connection of the guard with the casing, the said hook being adapted to engage a pin 17 projecting from the inner end of the strip 12 when the guard is in lowered position, thus securing this strip rigidly on the casing, it being understood that the hook 16 must first be thrown out of engagement with the pin 17 and the free end of the guard out of engagement with the locking member 15 before the guard can be swung upwardly and into inoperative and folded position. A box 18 is supported on the window casing 14, the said box having a cover 19 mounted to swing thereon and engaged by a spring 20 supported on the box to normally hold the cover 18 in closed position, a slot 21 being provided in the said cover for a purpose that will be hereinafter more fully disclosed.

Now when the guard 10 is folded within the box in the manner mentioned and the cover 19 is closed by the action of the spring 20, if it is desired to move the guard into open position, the cover 19 is first swung into open position against the action of the spring 20, after which the guard is swung downwardly into open position, with the free end of the guard secured to the casing 14 by the locking member 15 and the inner end of the strip 12 secured to the window casing by the hook 16. The cover 19 of the box 18 is now released and owing to the action of the spring 20 will swing into closed position, but in doing so will not interfere with the guard 10 in view of the provision of the slot 21 in the cover and through which the guard 10 extends when in lowered and unfolded position, as shown. Thus it will be apparent that when the cover is in closed position the horizontal edge of the cover, which forms the upper wall of the slot, will abut against the strip 11, form-

ing a part of the guard 10, and further hold the guard in open and locked position, thus preventing the guard from being raised in the event that it should accidentally become 5 disengaged from the spring-like locking member 15.

The device described is simple and durable in construction and can be placed upon a window casing without in any way interfering with the proper operation of the 10 sash or with the placing of screens on the window casing.

Although for the purpose of describing my invention, I have shown a particular 15 construction of my device, it will be understood that I do not limit myself thereto and that the scope of the invention is defined in the appended claim.

Having thus described my invention, I 20 claim:

In a guard for window casings, the com-

bination with a window casing, a member mounted to swing into folded or unfolded position on the window casing, a box carried by the casing and adapted to receive the 25 guard member when the same is in folded position, and a self closing cover hinged to the box and provided with a slot through which the guard member extends when the same is in unfolded position, the said cover, 30 when the guard member is unfolded, being closed and engaged by the guard member to lock the guard member in open position and prevent the guard member from being raised into folded position, until the cover 35 is swung into an open position.

In testimony whereof I affix my signature in presence of two witnesses.

BENJAMIN SAKREN.
